F. S. BARKS

JOURNAL-BOX

Filed May 3, 1922

UNITED STATES PATENT OFFICE.

FRANK S. BARKS, OF ST. LOUIS, MISSOURI, ASSIGNOR TO LINCOLN STEEL AND FORGE COMPANY, OF ST. LOUIS, MISSOURI, A CORPORATION OF MISSOURI.

JOURNAL BOX.

Application filed May 3, 1922. Serial No. 558,070.

To all whom it may concern:

Be it known that I, FRANK S. BARKS, a citizen of the United States, residing at the city of St. Louis, State of Missouri, have 5 invented a certain new and useful Improvement in Journal Boxes, of which the following is a full, clear, and exact description, such as will enable others skilled in the art to which it appertains to make and use the 10 same, reference being had to the accompanying drawings, forming part of this application, in which—

Figure 1 is a front elevational view partly in vertical section of my improved journal 15 box.

Figure 2 is a side elevational view partly in vertical section.

Figure 3 is a modified form of holding device.

20 Figure 4 is a horizontal sectional view illustrating the holding device shown in Figure 3.

Figure 5 is a horizontal sectional view showing another modified form of holding 25 device.

This invention relates to a new and useful improvement in journal boxes, the object being to construct a journal for use especially in connection with railway rolling 30 stock in which the box will be practically dustproof and oil tight, thereby enabling a charge of lubricating oil or grease to be introduced, whereby the moving parts and contacting surfaces may be well lubricated 35 and require the introduction of a new charge of lubricant only at infrequent intervals.

In the drawings, 1 indicates an axle and 2 a car wheel arranged thereon, these parts being of a standard and well known construction.

40 3 indicates a journal box, preferably in the form of a casting open at each end and observing substantially a cylindrical form. The side walls of this casting are provided 45 with laterally projecting lugs 4 constituting stops designed to co-operate with the pedestal jaws of a railway car truck in a manner well known.

50 5 indicates smaller lugs arranged at intervals between the lugs 4, and preferably having flat surfaces for engagement with the pedestal jaws.

55 6 indicates the protuberance on the upper wall of the box and extending from a thickened portion thereof to constitute a rocking

point contact on which the truck side frame rests. This protuberance is preferably arranged and described from an arc of a circle of smaller radius than the adjoining upper surface of the thickened wall on each side 60 thereof.

The bore of the box is preferably machine finished and of substantially the same diameter throughout the major portion of its length, this bore receiving a sleeve 7 of case 65 hardened metal forming a roller race for co-operating with the rollers 8. The inner ends of roller 8 co-operate with a washer 9, said washer being seated against webs 10 extending forwardly from the inwardly projecting flange 11, the aperture in said flange 11 being slightly larger in diameter than the axle at this point.

12 indicates a shroud formed on the inner end of the journal box casting, the space 75 13 produced by the peculiar form of the shroud constituting an enlarged oil or grease chamber. The shroud 12 provides a bearing surface 14, preferably elongated as shown, this bearing being undercut on its 80 inner side so as to provide an increased space for the grease or liquid in the chamber 13.

Bearing 14 co-operates with an antifriction thrust bearing ring 15, preferably made of bronze or other suitable material, said 85 thrust bearing ring 15 being cast upon and interlocked with a core ring 16, which is pressed or otherwise immovably secured in position on the axle 1, and preferably against the hub of the wheel.

90 17 indicates a thrust washer arranged between the ring 15 and the flange 11. This washer is preferably provided with a projection 18, shown in this instance, (see Figure 3) as a perforated lug, the purpose of 95 which is to lift the grease or lubricant from the lower portion of the chamber 13 and carry it to the top of the axle. This thrust washer thus becomes a lubricating ring whose function and mode of operation is 100 well understood.

In the bore of the journal box and near its forward end is a semicircular groove or recess 19 designed to receive the points or crowns of a star-shaped holding device 20. 105 This holding device is a rod or wire formed of spring metal and bent in the shape indicated in Figure 1, its ends being preferably disconnected so that the holding device will extend outwardly when inserted in position, 110

whereby the crowns of the bent portions will seat themselves in the groove 19. To remove the holding device, it is only necessary to collapse the ends until the crowns 5 are unseated. This holding device is designed to engage and hold in position an end closing plate 21, which plate is of approximately the same diameter as the bore of the journal box. The plate may be provided 10 with offset portions for the purpose of giving it strength and also providing a grease or lubricating space therebetween and the end of the axle, this space being more than sufficient to permit of end play of the axle 15 so that the axle will not come in contact with the plate in such play. A seat is provided for a bolt head at approximately the center of the plate, said bolt extending outwardly and passing through a central aperture 20 in a closing plate 22. This cap or closing plate is provided with an inwardly extending circular rib 23 which embraces the holding device 20 and the marginal edge of plate 22 is preferably machined to form 25 a rabbeted joint with the end of a journal box. A castellated nut 24 co-operates with a bolt 25 before referred to to hold plate 22 in position. Should it be desired to gain access to the interior of the box, for purposes of repair or inspection, the nut is removed, leaving the plate 22 to be taken off. The holding device 20 may now be removed, whereupon the end plate 21 can be taken 30 out. By jacking the box up, the rollers can 35 be taken out and replaced.

For purposes of charging the box with grease or lubricant, I provide threaded openings leading into the chamber 13 (see Figure 1) which may normally be closed by 40 a plug 27.

In Figures 3 and 4, I have shown a modified form of holding devices comprising a plurality of segments 20^a, which segments are spaced apart so that they may be readily inserted into and removed from the groove 45 19. When in operative position, these seg-

ments 20^a are prevented from leaving the groove 19 by means of the circular rib 23 on the cap plate, and serve to hold the end plate in position, they being placed under 50 shearing strain in performing this last mentioned function.

In Figure 5, I have shown the segments 20^b as slightly wider and the circular rib 23 as arranged in position to co-operate with 55 the outer faces of said segments rather than with the inner edges thereof, as shown in Figure 4.

What I claim is:

1. The combination of a cylindrical journal box, an end closing plate arranged therein, a sinuous holding device engaging said plate, and a cap plate secured to the end closing plate and bearing against the end of the box. 60

2. The combination of a journal box having a cylindrical bore, an end closing plate fitting in said bore, a holding device seated in said groove adjacent to said end closing plate, a cap plate seated against the end of 70 the journal box, and means for connecting the end closing plate and cap plate.

3. The combination of a journal box, an end closing plate, a cap plate, a holding device seated within the journal box and adjacent to said cap plate, and means for moving said plates towards each other whereby 75 said holding device is placed under shearing strain.

4. The combination of a journal box, an end closing plate, a holding device in the form of a rod or wire bent in the shape of a star, the points or crowns of which are seated in the groove in the journal box, a cap plate bearing against the end of the journal 80 box and provided with means for preventing displacement of said holding device from said seat, and means for connecting said two plates together.

In testimony whereof I hereunto affix my 90 signature this 19th day of April, 1922.

FRANK S. BARKS.
